US Trademark 2027507; filed on Aug. 2, 1994 by Smart Storage, Inc.
First use in commerce date: Dec. 2, 1992.*

Primary Examiner — Karen E Eldridge Powers(74) Attorney, Agent, or Firm — Sheridan Ross P.C.(57) CLAIM

The ornamental design for a display screen with icon, as shown and described.

DESCRIPTION

The sole FIGURE is a front elevation view of the display screen with icon.

The two icons shown in broken lines in the drawings are unclaimed features of the design. The remaining subject matter shown in broken lines illustrate the display screen which forms no part of the claim.

1 Claim, 1 Drawing Sheet(56)
